CARTRIDGE FUSE EXTRACTOR

Joseph John Dante, Bantam, Conn., assignor to
The Palmer Electric & Manufacturing Co.,
Waltham, Mass., a corporation of Massa-
chusetts

Application October 29, 1931, Serial No. 571,705

6 Claims. (Cl. 200—113)

This invention relates to cartridge fuses, and more particularly to a fuse holder having a manually operated bell-crank lever for extracting such a fuse with the minimum of effort without the use of fuse pullers, tongs, or other tools.

A further object of this invention is to provide a fuse extractor of the above nature in which the danger involved in removing the fuse will be greatly diminished.

10 A further object is to provide a device of the above nature which will be simple in construction, inexpensive to manufacture, easy to install and manipulate, compact, ornamental in appearance, and very efficient and durable in use.

15 With these and other objects in view there have been illustrated on the accompanying drawing, two forms in which the invention may be conveniently embodied in practice.

In the drawing:

20 Fig. 1 represents a front elevation of a fuse block having a pair of cartridge fuse clips mounted thereon, one of said clips being provided with an insulated extractor lever pivoted thereto.

Fig. 2 is an end view of the same.

25 Fig. 3 is a detail perspective view in separated relationship of the extractor lever and its associated fuse clip.

Fig. 4 is an end view on an enlarged scale of a modified form of the invention showing a spring for returning the extractor lever to its normal position.

30 It is well known to electricians that it usually requires a pull of from ten to twenty pounds to remove a fuse of the cartridge type from its socket clips, and in order to exert such a force it is necessary for the operator to insert his fingers under the fuse for practically its entire length with the consequent danger of injury from contact with the fuse clips.

40 By means of the present invention, the above and other disadvantages have been avoided. This has been accomplished by providing an insulating extracting lever attached to the fuse block which permits the operator to release one end of the fuse from its clip without touching the fuse or clips in any way. The fuse may then be readily grasped and separated from the other fuse clip without danger of shock.

45 Referring now to the drawing in which like reference numerals denote corresponding parts throughout the several views, the numeral 10 indicates an insulating base block having a pair of aligned U-shaped socket clips 11 and 12 of the conventional type. The socket clips 11 and 12 are adapted to be seated in a pair of depressions

13 and 14 formed in the top face of the base block 10 and are secured in position as by a pair of screws 15 and 16. The socket clips 11 and 12 are connected to a pair of terminal posts 17 and 18, respectively, by means of a pair of flat metal conductor strips 17a and 18a, so that these posts are adapted to be electrically connected by the insertion of a suitable cartridge fuse 19 in the clips 11 and 12. The fuse 19 is provided with the customary form of cup-shaped cylindrical metallic 10 end caps 20 and 21 which are adapted to be detachably snapped into the socket clips 11 and 12.

5 In order to facilitate the removal of a defective or "blown-out" fuse whenever desired, provision is made of a bell-crank extractor lever 22 pivotally mounted upon a rivet 23 having its ends seated in the opposite upstanding legs 24 and 25 of the clip 12. The rivet 23 is held securely in position by means of exterior heads 26 and 27 engaging the outer surfaces of the legs of the U-shaped clip 12. 20 The extractor lever 22 is preferably made of strong insulating material, such as molded phenolic condensation product, pressed fibre or steel covered with an insulating material, and comprises a relatively long flat recessed handle 28 and an integral 25 relatively short inwardly extending cam member 29. The extremity of the cam member 29 is provided with a raised rounded surface or nose 30 which is adapted to engage the under side of the metallic cap 21 for separating said cap from the 30 fuse clip 12 when the handle 28 is manually operated. The cam member 29 is provided with an intermediate transverse hole 31 adapted to be journaled on the rivet 23.

35 As will be understood, when the fuse 19 is assembled within the socket clips 11 and 12 in the position shown in Fig. 1, the handle 28 will project upwardly beyond the end of said fuse 19 in a position easily accessible to the operator's hand.

Operation

40

In operation, when it is desired to remove a fuse, it will only be necessary for the operator to grasp or press against the upper end of the handle 28 and swing it in a clockwise direction as 45 indicated by the arrow in Fig. 1 to the position indicated by the dot and dash lines. The nose 30 of the cam member 29 will thus be caused to force the end cap 21 of the fuse out of its socket clip 12 to the dotted line position shown in Fig. 1. The 50 operator may then grasp the body of the cartridge fuse 19 and detach the other end cap 20 from its clip 11.

The modified form of the invention shown in Fig. 4 is similar in most respects to the first form 55

- shown in Figs. 1 to 3, but instead of journaling the extractor lever 22 upon a headed rivet, a cotter pin 32 is employed for the journal member. A coiled spring 33 is also used for restoring the lever 22 to its original position after the fuse 19 has been ejected. A pair of upstanding lugs 34 and 35 integral with the base 10 are also provided to prevent axial movement of the cotter pin 32 or any other form of supporting means.
- 10 While there have been disclosed in this specification two forms in which the invention may be embodied, it is to be understood that these forms are shown for the purpose of illustration only, and that the invention is not to be limited to the 15 specific disclosures but may be modified and embodied in various other forms without departing from its spirit. In short, the invention includes all the modifications and embodiments coming within the scope of the following claims.
- 20 Having thus fully described the invention, what I claim as new, and for which it is desired to secure Letters Patent, is:
- 25 1. A holder for a conventional cartridge fuse, comprising a pair of spaced clips adapted to receive and clamp respective end caps of a fuse, each said clip consisting of a strip of resilient metal bent to an approximate U-shape, the arms of the U having their upper portions outwardly bowed to receive and fit against a cylindrical end 30 cap of a fuse, and an ejecting member mounted on the lower portions of the arms of one of said clips to rock on an axis directly under the fuse cap mounted in said clip.
- 35 2. A device of the class described, comprising a clip adapted to receive and clamp an end cap of a conventional cartridge fuse, said clip consisting of a strip of resilient metal bent to approximate U-shape, the arms of said U having upper portions outwardly bowed to receive and fit against a cy-
- lindrical end cap, and an L-shaped lever rockably mounted on the lower portions of said arms on an axis spaced inwardly from the end of a fuse in said clip.
3. A holder for a conventional cartridge fuse with cylindrical end caps, said holder comprising a pair of spaced alined clips adapted to receive and clamp the end caps of a fuse, each said clip including a pair of upstanding resilient fuse-engaging elements having converging portions arranged to be sprung away from each other by an end cap of a fuse as it is inserted into or removed from said clip, and an ejecting member rockably mounted on the upstanding elements of one of said clips.
4. In a cartridge fuse holder and ejector, the combination with a clip having side portions gripping the sides of a cartridge, and a U-shaped member journaled intermediate said side portions below the cartridge, of a lever for rotating said member to cause it to displace the cartridge from its hold in the clip.
5. A cartridge fuse holder and ejector comprising a clip having opposite spring portions for gripping a cartridge, a crank supported by and pivoted in said clip portions below said cartridge, and operating means for rotating said crank to cause it to displace the cartridge outwardly from said clip.
6. A cartridge fuse holder and ejector comprising a spring clip having opposite arcuate portions for gripping the sides of a cylindrical cartridge, a crank supported by and pivoted in said clip portions below said cartridge and adapted when rotated to displace said cartridge a distance sufficient to cause its axis to travel beyond the plane of the outer ends of said arcuate portions, and operating means for rotating said crank.

JOSEPH JOHN DANTE.
